CLAIM

The ornamental design for an air conditioner as shown and described.

DESCRIPTION

1. Air conditioner
- 1.1 : Perspective
- 1.2 : Front
- 1.3 : Back
- 1.4 : Left
- 1.5 : Right
- 1.6 : Top
- 1.7 : Bottom
- 1.8 : Exploded

The broken lines depict portions of the air conditioner that form no part of the claimed design; this design is for an air conditioner whose front upper part can be opened; this design has a fan door that covers the inside fans, so that the inside can be seen neatly when the front part is opened, and it serves as a flow path to send air flow; reproduction 1.8 is an exploded view showing that the fan door has been separated.
